OXYGEN BOTTLE HOLDER FOR MEDICAL USE

Hugo H. van den Bergh, 7103 Werner St.,
San Diego, Calif. 92122

Filed Dec. 20, 1973, Ser. No. 426,511

Term of patent 14 years

Int. Cl. D24—02

U.S. Cl. D83—1 B

FIG. 1 is a perspective view of an oxygen bottle holder for medical use showing my new design.

FIG. 2 is a rear elevational view thereof.

FIG. 3 is a side elevational view thereof as taken from the left hand side of FIG. 2.

FIG. 4 is a bottom plan view thereof.

I claim:

The ornamental design for an oxygen bottle holder for medical use, substantially as shown.
